August Biondi
INVENTOR

BY *Victor J. Evans*

J. Parker,
WITNESS:

ATTORNEY

UNITED STATES PATENT OFFICE.

AUGUST BIONDI, OF ALLENTOWN, PENNSYLVANIA.

KEY-CUTTING MACHINE.

Application filed April 2, 1923. Serial No. 629,447.

To all whom it may concern:

Be it known that I, AUGUST BIONDI, a citizen of the United States, residing at Allentown, in the county of Lehigh and 5 State of Pennsylvania, have invented new and useful Improvements in Key-Cutting Machines, of which the following is a specification.

This invention relates to key cutting or 10 milling machines, and the principal object is to produce a device of this nature which may be utilized for cutting keys having sloping notches as well as keys having abrupt or square notches, without having to insert different cutters in the machine.

Another object is to produce a device of 15 this nature in which an automatic feed may be had for feeding the key blank to the cutter synchronously with the operation of the cutter.

Another object is to provide a machine of 20 this class with tensioning means which may be rendered effective and ineffective at the will of the operator.

Another object is to produce a device of 25 this nature which shall be simple of construction, cheap to manufacture, and highly efficient for the purpose for which it is designed.

With these and other objects in view as 30 will be more apparent, the invention consists in certain novel construction and combination and arrangement of parts, the essential features of which are hereinafter fully described, are particularly pointed out in the appended claims, and are illustrated in the accompanying drawing, in which:—

Figure 1 is a top plan view of my improved key filing machine.

Figure 2 is an end elevation of the same.

Figure 3 is a section on line 3—3 of Figure 1.

Figure 4 is a detail view of the automatic feed device.

Figure 5 is a detail view of the follower.

Like characters of reference refer to like parts in all views.

Referring to the drawing in detail, 10 represents a bed-plate or base of the machine 50 which is provided with suitable brackets or

uprights 11, 12 and 13 for forming the bearings for various operating parts of the machine. A handle 14 and a pulley 15 may be securely fixed on the outer end of a shaft 16 having its bearing in the bracket 11 and carrying at its inner end a small gear 17 which meshes with a gear 18 keyed on a shaft 19. The shaft 19 has one bearing in the bracket 11 and has its other end supported by an adjustable center bearing 20 mounted in the upright 12. Secured to the shaft 19 exteriorly of upright 11 is a gear 21 which meshes with a small gear 24 keyed or otherwise secured to one end of a shaft or arbor 25, the other end of which is supported by a center bearing 26 mounted in the upright 13. It will now be understood that upon operation either by the handle 14 or by a belt passing around pulley 15, both of the shafts 19 and 25 will be rotated.

Mounted on the arbor or shaft 25 is a pair of cutters, numbered respectively, 27 and 28. The cutter 27 being a bevel cutter so as to cut keys which have irregularities of a sloping or inclined nature. Also mounted on the arbor 25 as above stated, is a cutter 28 which is particularly adapted for use in cutting square notches as will be readily seen from the drawing.

Mounted in the lower part of the upright 13 and in another upright indicated at 29 and extending laterally therefrom, are screw-members 30 which may be adjusted longitudinally of the arbor 25. Each of the members 30 carries an adjustable guide 31 which may be adjusted transversely of the arbor so as to compensate for wear in the adjacent cutter. The guide member 31 which co-operates with the cutter 27 is formed with a beveled end so as to follow the master key 90 in exactly the same way that the cutter will be cutting on the key blank. In like manner, the guide 31 which co-operates with cutter 28 is formed with a square tooth or projection adapted to fit into the notches in the 95 master keys with which it is to co-operate.

Mounted between bearings 32 secured in a bracket 33 which extends upwardly from the bed-plate 10 is a hub 34 which carries a forwardly extending arm 35 to the front end

of which is pivoted an arm 36 which extends laterally of the machine and is formed at its ends with a pair of vises 37 and 38. Said vises having movable jaws so as to grip keys or key blanks. The key blank will be gripped in the vise 37 which co-operates with the cutters while the master key will be gripped in the vise 38 so that its edge may be moved along the edge of the guide member 31, and thereby effect the movement of arm 36 so as to draw the key blank toward and from the cutter in forming the duplicate key. The vises are guided in their lateral movement by a supporting and guiding plate 53.

As indicated in the drawing, the vises may assume different positions, one of which is shown in full line in Figure 1, and the other of which is shown in broken line. In the full line position the vises are co-operative with the cutter 28 and its respective guide member 31, while in the broken line position, the vises are operative with regard to cutter 27, and its respective guide member.

There are two springs in this machine, one of which is indicated at 39 and the other at 40. The purpose of the spring 39 is to move the arm 36 and the attached vises into co-operative relation with the cutters, and the function of spring 40 is to move the arm 35 toward the right so as to position the key blank in operative relation to the cutter. However, when keys are being cut by a cutter 28 and such keys have deep notches, it is desirable that the springs 39 and 40 shall be rendered practically inoperative so that the arm 36 may be moved manually about its pivot and so that the arm 35 may be manually operated to feed the blank along as desired. For this reason the springs are connected in the manner which will now be described.

Spring 39 is anchored at one end directly to the bar 36 and at the other end is anchored to an eyelet extending from the edge of a disc 41 mounted for rotation on the end of a pin 42 which is mounted in the arm 35 and carries at its outer end a handle or finger-piece 43. By moving the finger-piece about its center, the pin 42 is turned and with it the plate 41, which may then be locked by a stop pin 44 against retrograde movement and will have effected a stretching or tensioning of the spring 39.

Spring 40 is anchored at one end directly to the arm 35 and has its opposite end anchored in an eyelet extending from the edge of a disc 45 mounted on a pin having its bearing in a box or bracket 47 extending upwardly from the bed-plate 10. On the opposite end of this pin there is mounted a handle 48, and by turning this handle from left to right in Figure 1, spring 40 will be placed under tension. As the handle

48 may be thrown slightly beyond its center, it will strike against the bed-plate and will be held there by the tension of the spring without requiring the use of the pawl.

When it is desired to automatically feed the key blank to the cutter as will usually be the case when keys are cut by the bevel cutter 27, the springs 39 and 40 are both tensioned and then an automatic control of the feed is brought into play. This automatic control consists of a nut 49 mounted on the shaft 19 and provided with a rearwardly extending arm 50 which carries a stop or control number 51. When it is not desired to have the automatic control operative, the nut 49 may be moved to the right hand end of shaft 19 which is not provided with threads, and operation of the shaft will not effect any lateral movement of the nut 49.

The specific construction of the nut as shown in Figure 4 shows two parts 50^a and 50^b which are hinged together at the bottom and which are secured at the top by means of a member 52.

Mounted on the end of the arm 35 is a cam or handle 53, and when the automatic control is to be operative, this cam is moved down to the dotted line position and then the nut 50 is moved along the shaft 19 until one of the members 51 rests at either side of cam 53. By operating the handle 14, the nut 50 will be moved along the shaft 19 and will permit movement of the arm 35 by the spring 40 so as to feed the key blank automatically to the cutter.

While I have described what I deem to be the most desirable embodiment of my invention, it is obvious that many of the parts may be varied without in any way departing from the spirit of my invention, and I therefore do not limit myself to the exact details of construction herein shown nor to anything less than the whole of my invention limited only by the appended claims.

What I claim is:—

1. In a device of the class described, the combination of an arbor, a cutter thereon, means for operating said arbor, a double vise for supporting a key and a blank, a guide member for co-operation with said key, a lever for operating said supporting means, a cam on said lever, and automatic means co-operative with said cam for controlling movement of said lever.

2. In a device of the class described, the combination of means for supporting a key blank, a plurality of cutters for co-operation with said means, and double vises co-operative with said cutters for moving a key blank from co-operative relation with one of said cutters to co-operative relation with the other of said cutters.

3. In a device of the class described, the

combination of an arbor, a cutter thereon, means for operating said arbor, a double 10
means for operating said arbor, a double vise for supporting a key and a blank, a
vise for supporting a key and a blank, a guide member for co-operation with said
guide member for operation with said key, 5 a lever for operating said supporting means,
and means for effecting tensioning of said means, and means for tensioning said spring. 15

4. In a device of the class described, the
combination of an arbor, a cutter thereon,

means for operating said arbor, a double 10
vise for supporting a key and a blank, a
guide member for co-operation with said
key, a lever for operating said supporting
means, a spring connected to said supporting
means, and means for tensioning said spring. 15

In testimony whereof I affix my signature.

AUGUST BIONDI.
